UNITED STATES PATENT OFFICE.

HENRY HILL, OF NOTTINGHAM, ENGLAND.

JACQUARD MECHANISM FOR EMBROIDERING-MACHINES.

SPECIFICATION forming part of Letters Patent No. 611,011, dated September 20, 1898.

Application filed January 28, 1897. Serial No. 621,102. (No model.) Patented in England February 6, 1896, No. 2,751; in Germany August 8, 1896, No. 91,184; in Switzerland November 14, 1896, No. 13,399; in Austria December 18, 1896, No. 47/335; in France December 24, 1896, No. 262,541, and in Belgium December 29, 1896, No. 125,419.

To all whom it may concern:

Be it known that I, HENRY HILL, a subject of the Queen of England, residing at Nottingham, England, have invented certain new and useful Improvements in or Relating to 5 Jacquard Mechanism for Embroidery-Machines, (for which I have obtained Letters Patent in Great Britain, No. 2,751, dated February 6, 1896; in Germany, No. 91,184, dated August 8, 1896; in Switzerland, No. 13,399, dated November 14, 1896; in France, No. 262,541, dated December 24, 1896; in Austria, No. 47/335, dated December 18, 1896, and in Belgium, No. 125,419, dated December 29, 1896,) of which the following is a specification.

This invention relates to improvements in jacquard mechanism such as that described in the specification filed with United States 20 application of July 14, 1896, Serial No. 599,129, for automatically moving the fabric-frame each stitch in any direction required.

The object of the present invention is to provide more perfect and convenient means 25 for moving longitudinally each of the two double racks G G' and L L', described and shown in the specification cited. The longitudinal movement of each of the racks is converted into the rotary motion of a pinion, engaging therewith, and the rotary movement of the pinion being communicated to a screw or a nut thereon the screw is moved longitudinally, and this movement is communicated to the embroidery-frame to which the said 30 screw is connected. The length of the longitudinal movement of the screw is determined by the angular distance through which it or the nut is rotated, and the latter is determined by the longitudinal movement of 35 the corresponding rack. The direction in which each screw or nut is rotated is determined by putting the pinion into engagement with one or other of the two racks.

The improved mechanism is arranged to 40 automatically move each double rack longitudinally a space equal to one, two, or more teeth, as required, and it is designed so as to give the long or short movements with equal smoothness and without the jerks or shocks 45 which invariably accompany the use of drop-

pers or distance-pieces in order that the machine may be run at a higher speed than has hitherto been practicable and the rate of production increased.

The invention will be best understood by 55 reference to the accompanying drawings, in which—

Figure 1 is a side elevation, and Fig. 2 an end elevation, of jacquard mechanism constructed according to my invention. Fig. 3 60 is a vertical cross-section taken on line X X of Fig. 1. Figs. 4, 5, 6, and 7 are views showing parts drawn to a larger scale than in Figs. 1 to 3.

Like letters indicate like parts throughout 65 the drawings.

The framing of the apparatus is formed by two standards A A, connected by three cross-stays B B' B².

C is a transverse shaft from which the 70 whole of the requisite movements of the apparatus are obtained. This shaft C is carried in bearings C', formed in or secured to the standard A A.

The apparatus is placed in a convenient 75 position, preferably at one end of the embroidery-machine, and the shaft C connected by suitable gearing to the main shaft of the said machine.

D D are two parallel shafts which are 80 mounted loosely and slide longitudinally in a bracket-bearing D', secured to the cross-stays B and in bearings D², formed in or secured to the cross-stay B'.

Secured to each shaft D is a diagonal frame 85 E, (see Figs. 1, 3, and 4,) provided with a corresponding number of steps, and connected to each of the said frames E is a corresponding number of pivoted jacks or arms F, provided with hooks or catches, the said jacks being 90 arranged in step-like series, as shown.

The jacks or arms F are connected to the frame E by adjustable brackets E', (see Figs. 1 and 4,) in which the jacks or arms F are pivoted, each of the said brackets being secured to a different step on the frame E. The jacks or arms are thus not only arranged one above the other, but are also each arranged in an independent vertical plane. 95

The upper ends E² of the frames E engage 100

in a longitudinal slide E³, secured to the cross-stay B. This slide is placed parallel to the shafts D and prevents the frames E and the shafts D from rotating about the axes of the latter.

5 G is a swinging frame which is pivoted at G' in bearings G², secured to or formed in the standards A A. This frame is reciprocated between the dotted extreme positions indicated at H H' by a cam, or, as shown, by a crank C' on the main shaft C and a connecting-rod I. The frame G approximates in form to the space occupied by the jacks F and is formed with an opening at each side 10 to receive each set of the said jacks. These openings are formed with steps in the same manner as the diagonal frames E, and each step is provided with a stud or projection J, adapted to engage with the hook of the corresponding jack. The studs J in each set are thus equal in number to the jacks F in each set and are disposed so that the hook of each jack, when the latter is raised, will engage with its corresponding stud J. The 15 studs J in the frame G, it will be seen, are arranged at gradually-increasing distances from the pivot or fulcrum G', and each will thus move through a different space, the amplitude of which is determined by its distance 20 from the pivot or fulcrum G. For example, the hook of the upper jack, marked No. 1, (see Fig. 5,) when raised will engage with the upper stud, which is also marked No. 1. The hook or the jack No. 2 when raised will 25 engage with stud No. 2, and so on throughout. It will be seen that No. 2 stud being farther from the fulcrum G' of the frame G than the stud No. 1 it will move a greater distance than stud No. 1, and it therefore follows if No. 2 jack be raised it will engage 30 with No. 2 stud and be moved a greater distance than No. 1 would have moved had the same been raised and engaged with its corresponding stud No. 1, and a less distance 35 than No. 3. It will also be seen that the whole of each set of jacks F, from Nos. 1 to 18, being secured to one frame E and the latter to the shaft D, the said shaft and frame E and the whole of the jacks in the set will 40 be moved the same distance as the jack which is raised and is thus put in action.

The distance of each of the studs J from the fulcrum G' is preferably arranged so that if No. 2 stud is brought into action it will 45 move the shaft D twice the distance it would be moved if No. 1 were brought into action, No. 3 three times the distance of No. 1, and so on, so that if No. 1 stud moves the shaft a distance equal to one unit or tooth of the 50 rack No. 2 will move it two units or teeth, and so on. It is therefore only necessary to raise one jack F for each movement in order to move the shaft D the requisite distance.

The position of the hook F' of the jacks F 55 is arranged in line with the frame G when the latter is in the extreme position shown at H', Fig. 1, so that whichever jack is raised it

is immediately engaged by its corresponding stud on the frame G, and the movement of the said jack is then identical with that of the stud with which it engages throughout. With this arrangement there is no jerk or shock either at the commencement or finish of the movement of the shaft D. The shafts D D may be connected to the racks in the 75 same manner as described in the specification cited or by other convenient means.

The jacks F are each raised by a vertical needle K, Figs. 3 and 6, the whole of which are mounted in a top slay secured to the 80 standards A A, and a triangular slay M, secured by a bracket M' to the cross-stays B². The upper ends of the vertical needles K are connected by threads K' to the vertical needles of a jacquard of any well-known and 85 suitable construction.

90 Springs K² are preferably interposed between the jack-threads K' and the vertical needles K in order that the selecting-needles in the jacquard may be raised at any point in the movement of the frame G or at a point where the jacks F are held down by the frame G. When the frame G returns to the position shown at H', the jack whose corresponding selector-needles in the jacquard have been 95 previously raised will be raised by the action of the spring, and its hook will engage with its corresponding stud J on the frame G, and a higher speed may thus be obtained. With 100 this arrangement the whole of the time occupied by the return movement of the frame G may be employed for the selecting movement of the jacquard, and the movement is consequently smoother.

105 Similar means may also be provided in connection with the above construction for moving the pinions into gear with the racks to those described in the specification cited. Four jacks N N' N² N³ are pivoted to corresponding rods T T' T² T³, the latter being 110 connected in pairs to the two opposite ends of the pivoted pinion-levers. The jacks N are pivoted at hooks or catches N⁵, (see Fig. 7,) which normally engage with studs O' on the two reciprocating arms O, secured to the 115 shaft, which latter is carried in bearings P', secured to or formed in the standards A A. The jacks N, which are to be inactive, are raised clear of the studs O, as shown in Fig. 7, by jack-threads Q, which are connected 120 to vertical needles in the jacquard. The arms O are reciprocated by a cam R on the shaft C through a lever R', connected to one of the arms O by a link R². The jacks N are returned to their normal position after 125 each movement by springs S, acting on the rods T T' T² T³.

I claim—

1. In a fabric-frame-moving mechanism for embroidery-machines the combination with 130 the main frame, the stationary frame, the hooked jacks pivoted to said frame, one above the other but in different vertical planes, connections between the said pivoted jacks and

the fabric-frame the swinging frame having pins at varying distances from its fulcrum adapted to engage with the hooks on the jacks the vertical needles and connection between 5 said needles and the vertical needles of the jacquard, substantially as described.

2. In a fabric-frame-moving mechanism for embroidery-machines the combination with the main frame, the two diagonal frames, 10 each provided with a corresponding number of steps, the jacks pivoted to each of said steps arranged diagonally with respect to a vertical line, connections between said pivoted jacks and the fabric-frame, the swinging frame having openings to receive the jacks, said openings formed with steps corresponding to the steps of the diagonal frames, and each provided with a pin with which the hook on the corresponding jack is adapted to 15 engage, said pins arranged diagonally with respect to a vertical line, the vertical needles and connections between said needles and the vertical needles of the jacquard; substantially as described.

20 3. In a fabric-frame-moving mechanism for embroidery-machines the combination with the main frame, the diagonally-arranged frames, the hooked jacks pivoted thereto,

arranged diagonally with respect to a vertical line the swinging frame having the pins 30 at varying distances from its fulcrum said pins arranged diagonally with respect to a vertical line and the vertically-operating needles adapted to lift the jacks to engage the pins of the swinging frame; substantially 35 as described.

4. In a fabric-frame-moving mechanism for embroidery-machines the main frame the diagonally-arranged frame, carrying the hooked jacks, arranged diagonally with respect to a 40 vertical line the swinging frame having the pins, arranged diagonally with respect to a vertical line, the vertically-moving needles operated by the selector-needles, of the jacquard and springs interposed between the 45 vertically-moving needles and the selector-needles of the jacquard; substantially as described.

In testimony whereof I have hereto set my hand in the presence of the two subscribing 50 witnesses.

HENRY HILL.
